UNITED STATES PATENT OFFICE.

EDWIN A. LIECKFIELD, OF CHICAGO, ILLINOIS, ASSIGNOR TO NIELS BUCK, OF CHICAGO, ILLINOIS.

COIN-CONTROLLED APPARATUS.

Application filed March 22, 1920. Serial No. 367,711.

To all whom it may concern:

Be it known that I, EDWIN A. LIECKFIELD, a citizen of the United States, residing at Chicago, in the county of Cook and State of Illinois, have invented a certain new and useful Improvement in Coin-Controlled Apparatus, of which the following is a full, clear, concise, and exact description, reference being had to the accompanying drawings, forming a part of this specification.

My invention relates to coin controlled apparatus and more particularly to a coin controlled apparatus adapted for use in vending newspapers.

It is well known that the daily newspapers and Sunday newspapers sell for different prices. A machine for selling papers must therefore be adapted to sell papers at either price. It is, therefore, an object of the invention to provide a coin controlled newspaper vending machine which is adapted to sell papers at different prices and in which the price may be changed at will between certain limits.

It is a further object of the invention to provide a device of the character described which is adapted to sell newspapers at one, two, five, six, and seven cent prices so that papers may be sold for any one of these prices.

It is a further object of the invention to provide a device of the character described in which the paper to be sold is partly disclosed so that the purchaser may know what paper he is to obtain when he operates the machine. It is also a further object to provide a vending machine of the character set forth in which the name of the paper and certain of the head lines on the paper will be visible so that these may serve to attract purchasers to the machine.

It is a further object of the invention to provide a coin controlled newspaper vending machine with a controlling device which will prevent the operator from obtaining more than one paper at a time.

It is a further object of the invention to provide a device of the character described wherein the papers will be arranged on edge and wherein means are provided for extracting the foremost paper from the pack of papers.

It is a further object of the invention to provide an operating device which cannot be

moved back toward normal position after once started on its delivery stroke until the 55 delivery stroke has been completed.

It is a further object of the invention to provide a coin controlled newspaper vending machine wherein all the operative parts are mounted upon a removable panel of the machine so that this panel and the operating parts carried thereby may be removed if the parts get out of order, and replaced by another panel carrying properly adjusted mechanism.

It is a further object of the invention to provide a device which will prevent the use of lead slugs or other slugs made of soft material. The device is also designed to prevent the use of slugs of larger diameter or 70 of greater thickness than the required coin.

With these and other objects in view which will become apparent from the detailed description of the device I have disclosed in the drawings one form which my invention may take which form is the best known to me at the present time. However, it is to be understood that by this specification and the accompanying drawings I do not intend to limit myself to the specific construction disclosed as modifications in the specific structure may be required in the manufacture thereof or may occur to those skilled in this art. The real nature and scope of the invention disclosed is to be determined from 85 the claims appended to this specification.

The same reference characters have been used to designate the same parts throughout the several views of the drawings in which—

Fig. 1 is a front elevation of a portion of 90 the casing equipped with my improved coin controlled newspaper vending mechanism. This figure shows a portion of the casing having mounted thereon a door upon which the parts are mounted.

Fig. 2 is a rear view of the mechanism shown in Fig. 1.

Fig. 3 is a rear view of the coin controlled locking mechanism similar to that shown in Fig. 2.

Fig. 4 is a vertical section taken approximately on line 4, 4 of Fig. 3 showing the operating slide in locked position and a coin about to be inserted in one of the slots.

Fig. 5 is a vertical section taken approximately on line 4, 4 of Fig. 3 and showing a coin in position where it will hold one of

the locking elements in inoperative position. This figure corresponds to Figure 4 but the newspaper extracting elements have been left out for sake of clearness.

5 Fig. 6 is a vertical section corresponding to Fig. 5 but showing the parts in an advanced state of operation.

Fig. 7 is a vertical section through the coin controlled locking mechanism taken on line 7, 7 of Fig. 6.

Fig. 8 is a horizontal section taken on line 8, 8 of Fig. 3.

Fig. 9 is a horizontal section taken approximately on line 9, 9 of Fig. 3.

15 Fig. 10 is a vertical section corresponding to Fig. 5 but showing one of the locking elements held in inoperative position by means of a slot closing member, this mechanism being used when the machine is operated with less than the entire number of coins for which the machine is adapted.

Fig. 11 is a perspective view of the slot closing device shown in Fig. 10.

In the drawings the reference numeral 12 indicates a portion of the casing of my improved vending machine. This casing may be made of wood, metal, or any other desired material or a combination of materials. The casing is provided with a swinging door 13 which is mounted upon hinges 14. The door is provided with a window 15 which exposes a portion of the newspaper 16 to view. The door is also provided with a lock 17 whereby it may be securely locked in closed position. The door 13 will usually be made of the same material as the casing 12. The lower edge of the door is cut away as shown at 18 and this cut away portion accommodates a panel 19 upon which the operating parts are mounted as a unit. The panel 19 completely closes the opening 18 as will be clear from Fig. 2. The lower portion of the door 13 is covered by a metal plate 20 which may be removably secured to the door 45 by means of screws 21. The panel 19 is securely mounted upon this metal plate by means of the screws 22, some of which are shown in Fig. 3 of the drawings. With this construction it will be apparent that when 50 the screws 21 are removed the plate 20 and panel 19 and all the operating mechanism mounted thereon may be removed as a single unit. This is very useful when the parts get out of order. The repair man does not 55 have to fix the machine on the spot but may replace the broken mechanism by a new one and take the broken mechanism to the shop for repair.

Bolted to the panel 19 are three brackets 60 23, 24, and 25. The bracket 24 is provided with a bearing portion 26 which is adapted to slidably receive one end of the operating rod or slide 27. The other end of this rod or slide passes through bearing 23 and is free

to slide therein. The rod 27 is provided with a recess 28 in its upper surface which recess accommodates a rack 29 which may be secured to the rod in any suitable manner. It is preferred to secure the rack in the recess by means of ordinary screws 30 so that the rack may be removed at any time should removal be necessary. The rod 27 is provided with a second recess 31 in its upper surface which recess is adapted to receive one edge of a locking plate 32, which locking plate may be secured to rod 27 by means of screws 33. The locking plate cooperates with elements later to be described for locking the rod against movement in a horizontal direction.

The bracket 24 is provided with a second bearing portion 34 which has keyed thereto one end of a rod 35, the other end of which is keyed to the bracket 25 previously referred to. Fixedly secured to the rod 27 and movable therewith is a pair of arms 36 and 37. These arms extend in parallel relation and have their upper ends forked as shown at 38 in Fig. 4 to straddle the rod 35. Each arm has a rearward extension 39 and these extensions are connected by means of a pin 40 which pin maintains the arms in spaced relation. The pin also forms an anchoring means for one end of the coiled spring 41, the purpose of which will later be set forth. The lower ends of the arms 36 and 37 may be conveniently secured to the rod 27 by means of ordinary pins. The arms 36 and 37 slide freely along the rod 35. Positioned between the forked ends of the arms and slidable and rotatable on the rod 35 is the newspaper engaging element 42 which has a downwardly extending arm having pivoted thereon a member 43 provided with a number of sharpened prongs which are bent in opposite directions as will be clear from Fig. 2 of the drawings. A lug 37' in the arm 37 bears against one side of the depending portion of the element 42 to support member 43 during the ejecting movement. The paper engaging element has an upwardly extending arm which is provided with a roller 44 which roller engages a cam member 45 which cam member is rigidly secured to the panel 19 as shown in Fig. 2 of the drawings. The cam is provided with an upwardly inclined portion 46 and a flat spring portion 47 which is narrower than the portion 46 as shown in Fig. 2. As the rod 27 is moved to the left in Fig. 2 the roller 44 rides over the spring portion 47 of the cam 45. When the roller reaches the end of the cam it is drawn toward the front wall of the casing by means of spring 41 which has its other end secured to the engaging element by means of the eyelet 48 as shown in Fig. 4. This movement of the paper engaging element causes the pronged

member 43 to move forwardly and engage the foremost newspaper 16 from the pack.

The papers rest on edge on a suitable support 49 and are held on said support by means of two vertical rods 50 which rods are spaced apart slightly less than the width of the papers so that the edges of the foremost paper rests behind the rod 50. The prongs on the member 43 engage the news-
paper when the rod 27 has reached the limit of its movement to the left. The prongs will therefore engage the paper and draw it out from behind one of the rods 50. This end of the paper will therefore swing forwardly and the next paper will bear against this rod. When the slide 27 starts to move backwardly toward its normal position the prongs draw the paper out from behind the other rod 50. Shortly after the paper is released from the second rod 50 the roller 44 engages the upwardly inclined portion 46 of the cam 45 and rides upon this inclined portion. This causes the member 43 to be drawn away from the paper and the paper falls down and out through a slot in the bottom portion of the machine. As the slide 27 approaches the end of its movement toward the right in Fig. 2 the roller passes from beneath the spring portion 47 of the cam and assumes the position shown in Fig. 2. The machine is then ready for another operation. This vending portion of my machine is made the subject matter of a separate application Serial No. 367,710; filed Mar. 22, 1920, and will not be claimed in this application except in so far as it cooperates with the coin controlled mechanism now to be described.

The screws 22 above referred to pass through the panel 19, the plate 20 and into threaded openings in the front plate 51 as will be clear from Fig. 4 of the drawings. This front plate is provided with a plurality of slots 52, 53 and 54. The slots 52 and 53 are of a size to receive one cent pieces while the slot 54 is slightly larger so that it will receive an ordinary nickel or five cent piece. Pivottally supported by the plate 20, the front plate 51 and a bushing 55 carried by the plate 20 is an operating shaft 56 which has secured thereto forwardly of the front plate 51 an operating handle 57. The operating shaft and handle may be conveniently formed of one piece bent at right angles as shown in the drawings.

Rigidly secured to the other end of the operating shaft 56 is a segmental gear 58 which meshes with the rack 29 on the rod 27. When the handle member 57 is rotated in a counter clockwise direction as shown in Fig. 1 the segmental gear 58 will be rotated in a clockwise direction as shown in Fig. 2 and will cause the rod or slide 27 to move

to the left as previously described. The parts so far described constitute a delivery mechanism which is adapted to deliver one newspaper at a time from a pack of newspapers resting on the support 49.

In order to prevent the operation of the slide 27 until after a coin or a plurality of coins have been inserted the following locking means are used. The locking plate 32 referred to above extends from the slide 27 toward plate 20 as will be clear from Fig. 8 of the drawings. This locking plate is provided with three openings 59, 60 and 61 which openings differ in diameter as will be clear from Fig. 8, the opening having the smallest diameter being positioned to the left adjacent an elongated slot 62 formed in the locking plate. At the right hand end of the slot 62 as shown in Fig. 8 is provided a downwardly curved cam portion 63 the purpose of which will be described later. The left hand end of the locking plate as shown in Fig. 8 is also curved downwardly as shown at 64. The purpose of this downwardly curved portion will also be described later.

Adapted to cooperate with the openings 59, 60 and 61 are three locking bolts 65, 66 and 67. These bolts having diameters corresponding to the respective openings in the locking plate 32 and are adapted to engage in said openings when the slide 27 and the locking plate 32 are in normal position. The bolts are adapted to slide vertically in a suitable housing 68 which housing is conveniently formed in two parts 69 and 70. The upper part 69 and the lower part 70 are held in fixed vertical alinement by means of the screws 71 shown in Fig. 7 of the drawings. Extending vertically through the parts 69 and 70 are three bores or openings 72, 73 and 74 which openings are adapted to slidably receive the three locking bolts previously referred to. The upper part 69 is also provided with transversely extending slots 75, 76 and 77 which slots align with the respective slots 52, 53 and 54 in the front plate 51 described above. The lower ends of the bores are enlarged as shown at 78 in Fig. 7 in order to provide space for the vertical movement of shoulders 79 which are formed on the respective locking bolts. Coil springs 80 are interposed between the shoulders 79 and the upper ends of the bores 78. A removable plate 81 is secured to the lower end of the part 70 and has three openings accommodating the ends of the locking bolts.

Each of the locking bolts has a cut away portion 82 which cut away portion extends substantially one half way across the locking bolt as will be clear from Fig. 9 of the drawings so that each bolt is semi-circular in the cross section at the cut away portion.

The cut away portion provides a lower shoulder 83 and an upper inclined shoulder 84 on each bolt. Interposed between the parts 69 and 70 is a plate 85 which is shown in plan view in Fig. 9 of the drawings. This plate has at its ends openings to receive the screws 71 and is provided with three substantially semi-circular notches 86 which engage the cut away portions of the locking bolts as shown in Fig. 9. The plate 85 therefore prevents rotation of the locking bolt but permits them to slide vertically. The shoulders 83 engaging the lower surface of the plate 85 limit the upward movement of the locking bolts in the housing 68. The space between the plate 85 and the upper shoulder 84 on each locking bolt is somewhat less than the diameter of the coin to be used to release the respective locking bolt. When the coin is inserted through one of the slots in the front plate 51 it engages the shoulder 84 on the bolt adjacent said slot and moves the bolt upwardly against the action of the spring 80. This upward movement of the bolt will result in withdrawing the lower end of the bolt from the respective opening in the locking plate 32. If all three of the locking bolts are in operation it will be necessary to insert three coins in order to release the slide 27 and the locking plate 32. If one of the locking bolts is held out of operation only two coins will be required.

Rigidly secured by means of screws 87 to the part 70 of the housing is a guide 88 which guide has extending vertically therethrough three openings 89, which are adapted to accommodate three pins 90 which pins slide vertically in the openings. Each pin is provided with laterally extending fingers 91 which extend into slots 92 which extend across the upper ends of the openings 89. The fingers 91 and the slots 92 prevent the pins from rotating in the openings 89. The upper end of each pin is inclined downwardly as shown at 92' in Fig. 5.

Fixedly secured to the operating shaft 56 is a plate 93 which is preferably shaped as shown in Fig. 7 of the drawings. This plate is adapted to swing upwardly around the shaft 56 as a center in a recess 94 formed in the door 13 adjacent the plate 20. The plate 93 has a beveled upper edge 95 which is adapted to engage the coins and move them inwardly as the plate is swung upwardly by means of the handle member 57. When the coins are inserted in the slots and pushed inwardly as far as is possible by means of the fingers the coins assume the position shown in Fig. 5 wherein they rest upon the plate 85 beneath the shoulders 84 and against the upper ends of the pins 90. The lower ends of the pins 90 rest upon the locking plate 32 as shown in Fig. 5 so that the pins prevent the coins from being

pushed beyond the shoulders 84. In order to prevent pins 90 from dropping out of the slots 89 when the mechanism is removed a narrow bar 96 shown in Fig. 3 extends between the fingers 90 and the front wall of the lower part 70 of the housing. The bar 96 is positioned above the fingers 91 so that it will prevent the fingers moving upwardly further than shown in Fig. 3.

In Figs. 10 and 11 I have shown means for holding one or more of the locking bolts in inoperative position when it is desired to operate the machine with less than the entire number of coins. This means comprises a plug portion 97 whose dimensions are equal to the diameter and thickness of the coin to be used. The plug portion carries a shield portion 98 which is adapted to fit across the slot in the front plate 51 as is shown in Fig. 10. After the locking bolt in question is raised to the position shown in Fig. 10 the plug 97 is inserted beneath the shoulder 84 as shown in Fig. 1. A key 99 is then inserted through a suitable opening in the rear end of the plug portion 97. The key engages the rear wall of the housing 68 and prevents removal of the plug and shield. In Fig. 3 I have shown an alternative means for holding any desired locking bolt in inoperative position. This means comprises a hook 100 pivotally mounted upon the inner surface of the door 13 and adapted to engage a suitable opening 101 formed in the upper end of the locking bolt. When the bolt is raised the hook may be inserted in the opening 101 and will hold the bolt in an operative position. It will, of course, be understood that a hook 100 may be provided for each locking bolt if so desired. The advantage of using the device shown in Fig. 11 is that the slot will be closed when the bolt is held in operative position whereas if the hook 100 is used additional means would also have to be used to close the slot in question.

The operation of my device is as follows: Let it be assumed that Sunday papers are to be sold at the price of seven cents each. The three locking bolts will then be left in operative position. If the operator desires to purchase a paper he will insert one cent pieces in the slots 52 and 53 and a five cent piece in the slot 54. After the coins are inserted they will assume the position shown in Fig. 5 wherein they rest upon the plate 85 and against the pins 90. This releases the slide 27 so that the operator may turn the handle 57 in a counter clockwise direction as shown in Fig. 1. This movement of the handle member causes the segmental gear 58 to move the slide 27 to the left in Fig. 2. The plate 93 will swing upwardly and the beveled edge 95 will engage the coins and move them inwardly

to approximately the position shown in Fig. 6. At approximately the same time the locking plate 32 will have moved to the right in Fig. 8 far enough to permit the pins 90 to drop down over the edge 64 of the locking plate. This position of the pins 90 is shown in Fig. 6. The inclined surface of the shoulders 84 will thereupon force the coins inwardly and cause them to roll downwardly into a suitable coin box 102. At approximately the same time that the last pin 90 drops off the locking plate, the roller 44 rides off the cam 45 and the spring 41 swings the pronged member 43 into contact with the foremost paper. Further movement of the slide 27 will cause one end of the paper to be drawn out from behind one of the rods 50. When the slide has reached the limit of its movement toward the left in Fig. 2 the operator swings the handle back to normal position. The prong on the member 43 will continue to hold the paper and will draw it out from behind the second rod 50. When the paper is released from the second rod 50 the roller 44 engages the upwardly inclined portion 46 of the cam 45 and the member 43 will be drawn away from the paper as shown in Fig. 4. The paper will then drop down and out through a suitable slot in the bottom of the machine.

After the coins have been released as described above the springs 80 will force the locking bolts downwardly as shown in Fig. 7. As the slide 27 returns its movement will be toward the right in Fig. 7. The downwardly turned end 64 of the locking plate will pass beneath the lower end of the locking bolt 65 shortly after the slide begins its return movement. The locking bolt 65 will therefore drop into the slot 62 and will prevent the operator from again moving the slide to the left in Fig. 7. Upon further movement of the slide toward the right in Fig. 7 the second and third pins 66 and 67 will drop consecutively into the slot 62 and this will insure a complete return movement of the slide. As the slide moves still further toward normal position the cam portion 63 on the slide will pass successively beneath the lower ends of the locking bolts. As the locking bolt 65 is of larger diameter than the opening 61 it will not drop into said opening nor will it drop into the opening 60 for the same reason. Likewise as the locking bolt 66 is of larger diameter than the opening 61 it will not drop in to the opening 61. The locking bolts will therefore slide over the top of the locking plate until the locking plate reaches its normal position whereupon the locking bolts 65, 66 and 67 will be in exact alinement with their respective locking openings 59, 60 and 61 and will drop therein to again lock the slide in normal position. If it is desired

to sell a paper for six cents the slot closing member shown in Fig. 11 will be inserted in the slot 52. If the paper is to be sold for two cents a slot closing member like that shown in Fig. 11 will be inserted in slot 70 54. If the price is to be only one cent then two of the locking bolts will be held out of operative position.

It will be noted from Figs. 5 and 6 that plate 85 is positioned slightly lower than the lower edge of the slots in the front plate 51. The coin will therefore drop downwardly as shown in Fig. 5 after it is inserted and as the coin completely closes the slot in the housing it will be practically impossible to extract the coin once it is inserted. The forward edges of the inclined shoulders 84 are sharp enough to bite into a lead slug or any other slug made of soft material and will effectively prevent the use of such slugs.

The panel 19 has a depression formed therein to receive the housing 68 and the housing is securely held in position by means of screws 103 clearly shown in Fig. 3 of the drawings. When the plate 93 is swung upwardly to the position shown in dotted lines in Fig. 7 it completely closes all of the coin slots and will prevent the insertion of coins or slugs while the machine is being operated. The beveled edge 95 passing close behind the plate 20 will shear or cut off any strings which may be attached to the coins for the purpose of withdrawing them after operation.

Having thus described my invention what I claim as new and desire to secure by United States Letters Patent is:

1. A device of the character described comprising a casing, a door formed therein, a plate removably secured to said door, a plurality of coin slots formed in said plate, coin controlled vending mechanism mounted upon said plate and removable therewith, and a front plate detachably secured to said plate, said front plate having a plurality of coin slots in alinement with the slots of said plate.

2. A device of the character described comprising a slide adapted to operate an article delivery element, a plurality of coin releasable means for locking said slide in normal position and permitting said slide to be moved to article delivery position after said locking means has been released, and a member engaged by said coin releasable means to successively lock the slide against movement toward article delivering position as it moves back toward normal position.

3. A device of the character described comprising a slide, a locking plate carried thereby, a plurality of bolts engaging said locking plate to lock the slide in normal position, said bolts being releasable by means of coins, a shoulder formed on said locking plate and means for causing said lock-

ing bolts to successively engage said shoulder as the slide is moved toward normal position.

4. Coin controlled apparatus comprising an operating slide adapted to be moved forwardly and backwardly, locking bolts each controlled by a coin for normally preventing forward movement of the slide but permitting said forward movement when they are released, and an abutment on said slide successively engaged by said bolts as the slide is moved backwardly.

5. Coin controlled apparatus of the character described comprising a slide, a locking plate carried by said slide, a plurality of openings formed in said locking plate, said locking plate having a slot formed therein adjacent said openings, coin controlled locking bolts normally engaging said openings, and adapted to successively engage in said slot as the slide is moved backwardly toward normal position.

6. Mechanism of the character described comprising a slide, a locking plate carried thereby, openings formed in said locking plate, coin releasable locking bolts adapted to engage said openings to prevent forward movement of the slide, a slot formed in said locking plate rearwardly of the openings and adapted to successively receive said coin releasable bolts as the slide is moved backwardly toward normal position.

7. A device of the character described comprising a slide, a locking plate secured to said slide, a plurality of openings formed in said locking plate, a slot formed in said locking plate rearwardly of said openings, a plurality of coin releasable bolts normally engaging in said openings and releasable from said openings when the coins are inserted and a downwardly turned end on said locking plate which is adapted to pass successively beneath said coin releasable bolts to cause the bolts to successively enter said slot as the slide is moved toward normal position.

8. A device of the character described comprising a slide, a rack formed thereon, a segmental gear engaging said rack to move the slide forward and backward, a locking plate carried by the slide, openings formed in said locking plate, a slot formed in said locking plate rearwardly of said openings, a cam formed at that end of the slot adjacent the openings, a downwardly turned end on the locking plate, and coin releasable bolts engaging in said openings to normally prevent forward movement of the slide, said cam and downwardly turned end causing said bolts to successively engage in said slot and pass therethrough to said openings as the slide is moved backwardly to normal position.

9. A device of the character described comprising an operating member having an

opening formed therein, a housing positioned above said operating member, a bolt slideable in said housing and engaging in said opening to lock said operating member, a shoulder formed on the bolt and adapted to be engaged by a coin inserted in said housing to withdraw said bolt from said opening.

10. A device of the character described comprising an operating member, a locking plate carried thereby, a housing positioned adjacent said locking plate, a coin slot extending through said housing, a bolt slideable in said housing and engaging said locking plate to lock the operating member, and a pin slideable in said housing to retain a coin in bolt releasing position, said locking plate being constructed so as to permit said pin to move out of the path of said coin.

11. A device of the character described comprising a slide a locking plate secured to said slide, a housing positioned adjacent said locking plate, a plurality of coin releasable bolts slideable in said housing and engaging said locking plate, pins slideable in said housing and supported by said locking plate in position to hold the coins in bolt releasing position, and means for moving the coins out of bolt releasing position when the slide is moved to operative position.

12. A coin controlled locking device comprising a housing, vertical bores formed in said housing, locking bolts slideable vertically in said bores, cut away portions formed on said bolts to provide shoulders adapted to be engaged by coins for releasing said bolts, and means formed on said housing to engage said cut away portions to prevent rotation of said bolts in said housing.

13. A coin controlled locking device comprising a housing formed in two parts, a plate inserted between said parts, bolts slideable in said housing and means formed on said plate to prevent rotation of said bolts in said housing.

14. A coin controlled locking mechanism of the character described comprising a two part housing, a plate inserted between the parts of said housing, bolts slideable in said housing, means within said housing to move the bolts in one direction, and means formed on said plate to prevent rotation of the bolts in the housing.

15. A coin controlled locking device of the character described comprising a two part housing, bolts slideable in said housing a plate inserted between the parts of said housing, to limit the movement of said bolts a detachable plate for permitting removal of the bolts from the housing, and means to prevent rotation of the bolts in the housing.

16. A coin controlled locking device comprising a housing, coin releasable bolts slideable in said housing, slots extending through said housing, shoulders formed on said bolts and adapted to be engaged by coins inserted in said slots, and means formed on said housing to prevent rotation of the bolts in the housing so as to maintain said shoulders in alinement with said slots.
- 10 17. Coin controlled mechanism of the character described comprising a housing having coin slots formed therethrough, the width of said housing being less than the diameter of the coin to be used, coin releasable bolts slideable in said housing and adapted to be moved into inoperative position when coins are inserted in said slots, and means to move said coins entirely through said slots to permit the bolts to move to operative position.
- 15 18. A device of the character described comprising a supporting member, a shaft carried by said supporting member, a housing secured to said supporting member and having slots formed therethrough for receiving coins, the coins when positioned in said slot projecting outside of said housing and means carried by said shaft for forcing the coins through said slots when the shaft is operated.
- 20 19. A device of the character described comprising a plate, a housing mounted adjacent said plate and having coin slots formed therethrough, a shaft rotatably supported by said plate and means carried by said shaft and movable between said housing and said plate to close said slots when the shaft is operated and to move coins into said slots.
- 25 20. A device of the character described comprising a front plate having a coin slot formed therein, a housing positioned adjacent said front plate and having a coin slot formed therein in alinement with said first named coin slot, a pin slideable on said housing adjacent said second named slot and adapted to retain a coin in said second named slot, means for removing said pin from said slot and means for forcing the coin inwardly through said slot.
- 30 21. Coin controlled vending mechanism of the character described comprising an operating member adapted to operate a vending element, a coin controlled means for normally maintaining said operating member in normal position, said coin controlled means comprising locking members successively engaging an abutment on said operating member to lock said operating member against forward movement in successive stages during the rearward movement of the operating member.
- 35 22. A device of the character described comprising a slide, a locking plate secured to said slide, a plurality of openings of dif-
- ferent diameters formed in said slide, a plurality of coin releasable locking bolts engaging said openings to lock the slide in normal position, said bolts having diameters corresponding to the diameters of said openings, means to move the slide forwardly after it is released and to move it backwardly after operation, the bolts and openings being so arranged that the bolts of larger diameter will slide over the openings of smaller diameter during the initial forward movement of the slide.
- 40 23. A device of the character described comprising a slide, means to move said slide forwardly and backwardly, a plurality of coin controlled means normally preventing forward movement of the slide, and a member engaged by said coin controlled means to successively lock the slide as it is moved backward toward normal position.
- 45 24. Coin controlled apparatus comprising a slideable member, means to move said slideable member forward and backwardly coin controlled bolts normally holding said slideable member against forward movement and adapted to be held in inoperative position by coins inserted in the device, means for retaining said coins in bolt releasing position and means on said bolts for moving the coins out of bolt releasing position as the slideable member is moved forwardly.
- 50 25. A device of the character described comprising a slide, means to move the slide forward and backwardly, coin controlled bolts normally locking the slide against forward movement and adapted to be released when coins are inserted, means to retain the coins in bolt releasing position said means being adapted to release said coins to successively permit said bolts to move to locking position, as the slide is moved forwardly, and means whereby said bolts successively lock the slide against forward movement after the slide is started on its rearward movement.
- 55 26. A device of the character described comprising a slide, means to move the slide forwardly and backwardly, a housing adjacent said slide having coin slots extending therethrough, bolts slideable in said housing and engaging the slide to prevent forward movement of the same, said bolts being released by means of coins inserted in said slots, means to retain said coins in bolt releasing position during the forward movement of the slide, and means on said slide successively engaged by said bolts to prevent forward movement of the slide after it has begun its rearward movement.
- 60 27. A device of the character described comprising a slide, a locking plate carried by the slide, a housing adjacent said locking plate, bolts slideable in said housing and normally locking said slide against forward movement, said housing having coin slots

formed therein for receiving coins to release said bolts, pins slidable in said housing and held by said locking plate in position to prevent coins passing entirely through said slots, said locking plate successively releasing said pins and bolts during the forward movement of the slide and means whereby

said bolts successively engage the locking plate during rearward movement of the slide.

10

In witness whereof, I hereunto subscribe my name this 16th day of February A. D., 1920.

EDWIN A. LIECKFIELD.
